UNITED STATES PATENT OFFICE.

CYRUS F. BRACKETT, OF PRINCETON, NEW JERSEY.

ELECTRO-MAGNETIC DYNAMOMETER.

SPECIFICATION forming part of Letters Patent No. 287,800, dated November 6, 1883.

Application filed June 20, 1883. (No model.)

To all whom it may concern:

Be it known that I, CYRUS F. BRACKETT, a citizen of the United States, residing at Princeton, in the county of Mercer and State of New Jersey, have invented a certain new and useful Electro-Magnetic Dynamometer, of which the following is a specification.

The nature of this invention and the proper methods of applying it will be easily understood from the following exposition, reference being had to the accompanying drawings, and to the letters affixed thereto.

When the armature of a dynamo-machine is made to revolve, the circuit being closed, there is developed between the armature and the field-magnets a mechanical couple, which tends to cause the field-magnets to revolve in the same direction with the armature. If the field-magnets were balanced without friction, and were otherwise unobstructed, so as to be free to revolve, they would do so with increasing velocity, till at length they would perform their revolutions in the same time with the armature, when the current would be reduced to zero. If, instead of permitting such revolution, we were to apply another couple tending to make the field-magnets revolve in the opposite direction, and were to make its value equal to that of the couple set up by the current, the field-magnets would remain at rest. We could always know the value of the couple thus applied, since it might be applied as a known pressure at a definite point on a lever-arm. We should then, in addition, only need to know the velocity of the armature in order to determine the energy sought. How these principles are embodied in my invention I now proceed to point out.

Figures 1 and 2 represent a dynamo-machine to which my invention is applied standing in two positions at right angles to one another.

The field-magnets A are supported on two uprights, S, which are fixed to the base O. The support is effected by means of a rigid bar, G, through whose ends pass the rods K. One of these rods terminates in a knife-edge and the other in a point, both of hard steel. These terminations rest, the one in a groove, the other in a cone-shaped cavity, also both of hard steel. This arrangement is designed to prevent displacements of the magnets from acci-

dental shocks. The rods are so adjusted by means of nuts and screws that the opening between the field-magnets, in which the armature revolves, shall be concentric with it, and the lower points of the rods are so arranged that a line joining them shall be coincident with the armature's axis of revolution. Lever-arms X and X' are so attached to the field-magnets that a line drawn along their upper edges shall pass through the axis of revolution of the armature. These lever-arms are graduated in equal parts, reference being had to some convenient unit of length. The zero-points of the graduation lie in the axis of revolution of the armature. The lever-arms are designed to carry sliding weights of known value, to be employed in producing the couple which acts in opposition to that set up by the current, as before pointed out; or springs may be used instead of weights. The whole magnet system, together with its supporting-bar and attachments, is so balanced that its center of gravity is very slightly below the line passing through the knife-edge and point on which it rests, as in the common balance. The arc through which the lever-arms can turn is kept within limits convenient for observation by means of any convenient stops, which need not be specified.

Suppose the machine, in the position shown in Fig. 1, to be set in motion, the circuit being closed, and the revolution of the armature being in the direction of the hands of a watch, the field-magnets, being free to turn through a small arc, will be displaced from their position of horizontal equilibrium, so that the arm X will be raised and the arm X' will be depressed. A sliding weight, W, (not shown,) is to be placed on the arm X and moved, if necessary, till the couple thus applied is equal to that developed by the action of the machine. The energy expended during one revolution of the armature is now found by taking the product of the number of units in the circumference of the circle, whose radius is determined by the position of the weight on the lever-arm, by the number of units contained in the weight. This product multiplied by the number of revolutions per minute gives the energy expended per minute; or, if W be the weight in pounds, a the length of the effective lever-arm in feet, and

n the number of revolutions in a minute, we may express the result by a formula, thus: Ft. lbs. per min. = $W \times 2\pi a \times n$. The velocity of revolution is ascertained by means of a "counter," which is applied, in the usual way, at the center *H*. In a precisely similar way the mechanical energy developed by the machine when used as a motor is ascertained, reference being had to the direction of revolution 10 which the field-magnets tend to assume.

The application of the main principle of the invention herein set forth is not limited to the special form of machine shown in the accompanying drawings, but it may be made as 15 well to all machines which produce a current of electricity by the revolution of an armature in a magnetic field, or, conversely, by the revolution of a magnetic field about an armature.

Any convenient form of support for the 20 field-magnets which will permit the requisite freedom of motion may be adopted instead of the one herein described.

This invention may be employed also in 25 measuring the energy delivered by any revolving shaft in the performance of its duty as a prime motor. For this purpose an armature is secured to the shaft whose energy at a given speed—say that maintained when doing its usual duty—is to be measured, and 30 suitable field-magnets are properly placed and supported, so as to act in accordance with the principles already set forth. The usual work is now thrown off, and the circuit of the armature and magnets is closed through a resistance which can be varied at pleasure. Now, 35 the current produced, and consequently the amount of work done upon the electro-magnetic system, will depend on the resistance of the circuit. This resistance is therefore to be 40 varied until the speed of the shaft is made equal to the given speed. The energy delivered to the electro-magnetic dynamometer is then computed as heretofore described.

It is evident that by employing a suitable 45 means of determining the value of the current produced with different speeds and with different resistances in the circuit a table may be constructed which shall contain these factors of current, speed, and resistance, together 50 with the energy corresponding, which can be found as before pointed out. The advantage of such a table would consist in its ready application when once prepared in cases where for any reason it is desired to keep the field- 55 magnets fixed, as is the case with ordinary forms of dynamo and magneto machines.

Having now fully described my invention and pointed out its applications, what I desire to claim and secure by Letters Patent is—

60 1. The process of measuring the mechanical energy of a revolving shaft, which consists in measuring the mechanical couple set up between the elements of a magneto-electric or

an electro-magnetic system, where one of such elements revolves with the energy to be measured and the other is held fixed, substantially as shown and described. 65

2. The process of measuring the energy of a revolving shaft, which consists in measuring the mechanical couple set up between the 70 elements of a magneto-electric or electro-magnetic system, where one of such elements revolves with the energy to be measured and the other is held fixed, by measuring the couple necessary to hold such other element fixed, 75 substantially as shown and described.

3. The process of measuring the energy expended on a dynamo or magneto machine when used as a generator, or derived from such machines when used as motors, which 80 consists in measuring the mechanical couple set up between the revolving element and the stationary element of such machine, substantially as shown and described.

4. The process of measuring the energy 85 expended on a dynamo or magneto machine when used as a generator, or given out by such a machine when used as a motor, which consists in measuring the mechanical couple set up between the revolving element and the stationary element of such machine, by measuring the couple required to hold such second element stationary, substantially as shown and described.

5. In an electro-generative or an electro- 95 motive system, the combination of a revolving and a rocking element with means, as described, of measuring the mechanical couple set up between the two elements, substantially as and for the purposes set forth. 100

6. In an electro-generative or an electro-motive system, the combination of a revolving element and a stationary element with means, as described, of measuring the force required to hold the said second element stationary, substantially as and for the purposes 105 set forth.

7. In an electro-generative or an electro-motive system, the combination of a revolving element with a rocking element having 110 lever-arms and weights adjustable on the same, whereby the said rocking element is balanced, substantially as and for the purposes set forth.

8. In an electro-generative or an electro-motive system, the combination of a revolving armature with field-magnets mounted on knife-edge and point, as described, and having lever-arms with weights adjustable thereon, whereby the mechanical couple set up between the armature and the field-magnets may 120 be measured, substantially as and for the purposes set forth. 115
